VACUUM CONTROL OF SPARK ADVANCE

James L. Arthur, Anderson, Ind., assignor to
General Motors Corporation, Detroit, Mich., a
corporation of Delaware

Application February 24, 1936, Serial No. 65,358

27 Claims. (Cl. 123—117)

This invention pertains to the art of automatic ignition controllers for automotive engines, and is directed to that type of fluid operated controllers that effect a shift in ignition timing in response to pressure variations within an engine fuel induction pipe, or engine intake manifold.

One device of the kind, is disclosed in the patent to Stone 1,288,736, issued December 24, 1918, and in which a contraction chamber, having a movable part linked to an adjustable part of a timer mechanism, responds to low pressures within the fuel induction pipe, when in communication therewith through an appropriate valved passage, for moving the adjustable timer part to effect a change in ignition timing. By the Stone construction, it is proposed to cut off the application of reduced pressure to the contraction chamber, while the engine is running at idle, so that a spring incorporated in the contraction device will effect a retard of timing, and thence it is also proposed to admit the low pressure to the contraction chamber in varying and increasing amounts as the throttle valve is opened beyond idling position, so that an increasing advance of timing will be effected for the corresponding engine speeds.

While there are many prior art devices directed to the same art, of which Stone above mentioned is but a single example, all of the prior art devices fail to give complete control of ignition timing for all conditions of engine speed and car road torque. One particular point at which the prior art devices fail, is in giving any adequate control of ignition timing, for the higher speeds of the entire speed range. The prior art devices, therefore, ignore the fact that it is necessary from a standpoint of efficiency, or that it is at all desirable to modify the automatic advance in timing during the higher speed operating conditions. As a result, timer control mechanisms of the prior art devices give too great a shift of automatic timing, and continue the shift by automatic mechanism over too great a range of engine speed. In other words, the automatic shift of spark timing lasts too long and extends too far toward the high speed end of the engine speed range.

It has been discovered by applicant, that for best efficiency and economy in engine operation, there is possible a basic control of spark timing by speed responsive mechanism, that will fit fairly closely the minimum demands for average operating conditions, and upon which basic control there is to be superposed further control that will take care of the extremes of demands

for timer regulation. This basic control is what may be called an initial timer setting, to which is joined a normal control of spark advance by speed responsive mechanism. Over this basic control, it is desired to have no timer shift at or during engine starting and idling speeds, and during the extreme high engine speeds, but to produce a rather abrupt and fixed amount of timer shift throughout the band of engine speeds situated between the idling speeds and the extreme high speeds, which latter shift shall be superposed over the centrifugal or normal control.

It is therefore an object of this invention to provide for effecting ignition timer control throughout the entire range of engine speeds and/or vehicle road torques.

A further object of the invention is to provide a method for controlling a suction operated timer shifting mechanism, such that a retarded spark timing relation will be accomplished for engine starting and idling, such that a substantial fixed amount of advance spark timing will obtain for all moderate engine speeds above idling, and such that the advance of ignition timing will be reduced to a basic control for higher engine speeds, or for those speeds greater than moderate engine speeds.

Another object of the invention is to make use of the throttle shaft, when opened to a certain position, as a cut-out for spark control connections.

Another object of the invention is to accelerate the cut-off of the motive unit at a designated point in the range of engine speeds.

A still further object is to provide a passage in the throttle shaft, opening into the carburetor side of the throttle valve so as to drop the vacuum at the distributor diaphragm when the engine and car road torque reaches the point where the spark should be retarded, particularly at high speed.

These several objects are accomplished by means of an interruptible passage, joining the fluid connections to the contraction unit, and controllable for negating the suction effect within the fuel induction pipe upon the contraction unit at a selected point or points in the range of throttle movement.

Part of the interruptible passage includes a cross-bore or duct through the fuel throttle shaft, and so located that shaft rotation will establish communication between the cross-bore and the fluid connection to the contraction unit only at a desired relation of throttle opening. At that desired relation, the contraction unit is exposed

to the low pressure zone through a primary passage, and the newly effected communication through the interruptible passage forms a bypass around the primary passage to the high pressure zone of the induction pipe. When the throttle valve is closed or nearly closed the contraction unit is exposed to the fluid pressure in the high pressure zone at the primary port, and responds accordingly. When the throttle valve is opened 10 to the point where the by-pass communication is sufficiently established, the contraction unit is then exposed to the combined effect of the fluid pressure of the low pressure zone at the primary port, and of the high pressure zone at the orifice 15 of the interruptible passage. In consequence of the latter, a complete retraction of the advance mechanism is effected soon after communication is perfected between the interruptible passage and the primary passage.

20 Further objects and advantages of the present invention will be apparent from the following description, reference being had to the accompanying drawings wherein a preferred embodiment of the present invention is clearly 25 shown.

In the drawings:

Fig. 1 is a view illustrating the layout of the timer control mechanism forming the subject matter of the instant invention, certain parts 30 of the construction being shown in section, and certain other parts being broken away for the purpose of clear illustration.

Fig. 2 is a view in elevation, with parts shown in section, illustrating parts of the fluid connection to the engine intake pipe, when the throttle valve has been opened to a point above idling speeds. The section taken is indicated by the line and arrows 2—2 of Fig. 4.

Fig. 3 is a view similar to Fig. 2, illustrating 40 the throttle valve open to a greater degree, and at which position the interruptible passage is being opened.

Fig. 4 is a transverse sectional view through the fluid connections to the induction pipe, substantially as indicated by the line and arrows 45 4—4 of Fig. 3.

Fig. 5 is a fragmentary sectional view substantially as indicated by the line and arrows 5—5 of Fig. 2 and illustrating the relation of parts 50 to accomplish the low speed suction cut-off.

Figs. 6 to 10 inclusive illustrate a modification of the construction, Fig. 6 being a transverse sectional view through the fuel induction pipe, substantially at the axis of the throttle shaft, 55 while Fig. 7 is an elevational view of the same, showing parts in section substantially as indicated by the line and arrows 7—7 of Fig. 6. Figs. 8 and 9 are views similar to Fig. 7, the throttle valve having been moved to different positions. 60 Fig. 10 is a layout somewhat similar to Fig. 1, but illustrating the throttle valve in the wide open position, and the contraction unit in its resulting condition.

Fig. 11 is a group of conditions curves, illustrating the pressures obtainable in inches of mercury (H_g) depression, for various engine speeds.

Fig. 12 is a group of results curves illustrating the timing alterations that may be effected by the mechanism disclosed.

70 Referring to the drawings, and first with particular reference to the modification illustrated in Figs. 1 to 5, the layout depicted in Fig. 1 illustrates the relation of the elements contributing to the complete control of spark timing devised 75 by applicant. The reference numeral 10 indi-

cates a fragmentary part of the engine base or frame that provides a well for receiving the stem or shank of an ignition distributor, the cup like housing of which is indicated at 12. Pivot about the shank of the cup 12 there is a bracket 5 member 14, an extension of which provides an arcuate slot 16 for reception of a holdown screw and tension device 18, that permits of oscillation of the bracket 14 within certain limits with respect to the engine base 10. There is also provided a clamp arm 20 embracing the stem of the distributor cup 12, and maintained in rigid engagement therewith by means of a clamp screw 22 passing through one of the parallel extensions 24 and threaded into an oppositely disclosed 15 extension 26. This organization provides a pair of plate members represented by the parts 14 and 20 both disposed about the shank of the distributor cup between the cup 12 and base 10, and relatively movable through the agency of mechanism later to be described.

The distributor mechanism also embraces a shaft 30 having a geared relation with rotative parts of the engine in general, for driving a circuit breaker cam 32 operable to periodically 25 actuate a circuit breaker lever 34. The circuit breaker lever is provided with an insulated sleeve 36 that supports the lever for oscillation about a pivot post 38 carried by a breaker plate 40. The plate 40 is supported within the distributor cup 30 12 by means of lugs 42 rigidly held to the cup 12 by appropriate screws 44. Also mounted upon the breaker plate 40 there is a contact support or bracket 46 providing a fixed contact 48, co-operable with a movable contact 50 supported by 35 the circuit breaker lever 34. Operation of the circuit breaker lever is perfected by reason of a rubbing block 52 that is periodically engageable by one of the crests of the rotating cam 32. The electrical connection of the circuit breaker is 40 completed by means of a leaf spring conductor 54 secured thereto and wrapped about the insulated sleeve 36, the other end of the spring being secured under the head of a terminal screw 56 insulating supported in the wall of the cup 45 12, and to which the usual electrical connection of the current source is made.

The driving connection between the rotatable part of the engine and the cam 32 also includes a speed responsive mechanism that permits of angularly shiftable relation between the shaft 30 and the cam 32 in response to variations in engine speed, at 1 includes what is known as a weight base 58 provided with pivot posts 60 about which oscillate flyweights 62 during variations 55 of engine speed. The flyweights each provide a camming arm 64 engageable with a cam bar 66 secured in rigid relation with respect to the cam 32. The camming portions of the flyweight and cam bar are maintained in engageable rollable 60 relation by means of a spring 68 hooked about the pivot post 60 and a rigid part 70 of the circuit breaker cam assembly. Inasmuch as the distributor mechanism thus far described is well known to those experienced in the art, it is not 65 deemed necessary to go further into the discussion and description of the same. Therefore, suffice it to say, as the speed of the engine is increased, the flyweights 62 will be thrown out toward the outside of the distributor cup 12, and 70 in doing so the cam arm 64 will rotate the circuit breaker cam 32 somewhat in advance of the rotation produced by the geared connection with the shaft 30, which will thereby effect an advance in circuit breaking through the points 48 75

and 50 as the engine speed increases, all in accordance with the curve D appearing on the group of results curves, in Fig. 12.

The curve D in Fig. 12, sets out the basic spark timing control relation mentioned earlier, and will hereinafter be referred to as the normal spark timing curve, over which additional timing adjustments are to be effective. In its entirety, this normal or basic spark timing curve consists of a horizontal branch indicated by a and a uniformly ascending branch indicated by b. The branch a is here shown to amount to about 10° advance for the initial spark setting, and extending throughout engine speeds from rest through idling engine speeds to about 14 M. P. H. engine speed. At about 14 M. P. H. the centrifugal mechanism cuts in, and effects a comparatively regularly ascending branch b, in accordance with increase of engine speed. The increasing shift is maintained substantially constant to about 60 M. P. H. engine speed, whereupon the timer advance flattens out to a definite setting of about 50° ahead of top dead center for engine speeds above about 70 M. P. H.

Reverting to the illustration appearing in Figs. 1 to 5, fluid operated means, responding to the variations of pressure in the engine intake pipe, are provided for effecting a spark timing control to be superposed upon the normal spark timing curve. Contributing to this end, a fluid operated unit or contraction chamber 72 is mounted upon an angular extension 74 of the bracket member 14, and is provided with means for rotating the distributor mechanism about the rotating cam shaft 30, for additionally effecting a shift in spark timing. The contraction chamber 72 comprises a pair of cup like members 76 and 78, the peripheral edge of one of which is spun over the peripheral edge of the other, substantially as indicated at 80, so as to clamp the edge of a membrane or diaphragm 82 therebetween, and provide a substantially fluid tight chamber 84 bounded by the cup member 72 and membrane 82. Disposed within the fluid tight chamber 45 there is a spring 86, one end of which seats within a cup or washer member 88, and that urges the diaphragm or membrane 82 away from the bottom of the cup member 72, so as to enlarge the chamber, yet permit a collapsing of the same upon exposure to reduced pressure. A link 90 is secured to the membrane 82 by means of a rivet 92 passing through the washer 88 and membrane, and clamping an extension of the link 90 thereto. The link 90 is notched or necked in at 94 and passes through an aperture or slot 96, provided by the angular portion 74 of the bracket member, whereby stops are provided that limit the overall movement of the link 90. The opposite end of the link 90 has a pivotal connection with a part 98 of the clamp arm 20.

This organization of elements is such that lineal movement of the link 90 through the slot 96 of the bracket member will produce relative rotation or oscillation between the plate members 14 and 20. Since the bracket member 14 is but loosely pivoted about the shank of the distributor cup 12, and firmly held in position on the engine frame member 10 by means of the tension device 18, and since the clamp arm 20 is rigidly secured to, and non-rotative with respect to the shank of the distributor cup 12, then, relative rotation or oscillation between the plate members 14 and 20, will likewise cause relative rotation or oscillation of the distributor cup 12 with respect to the engine frame member 10. Thus, when oscillation

or rotation of the distributor cup 12 is effected, while the circuit breaker cam 32 is being rotated, a shift in the time of circuit breaker operation is effected, which shift will be dependent for effecting timing advance or timing retardation upon the direction of relative movement with respect to the direction of circuit breaker cam rotation. If the shift is in the same general direction as the direction of circuit breaker cam rotation, then the effected shift in timing will result in retardation, but, if the shift is in the opposite direction to that of circuit breaker cam rotation, then the effected shift in timing will result in an advance in timing, because in the latter instance the circuit breaker operation occurs earlier in point of time than it otherwise would without the attendant shift.

For the purpose of actuating the membrane or diaphragm 82 of the contraction chamber, fluid connection is made between the chamber 84 and the interior of the engine induction pipe, and includes appropriate coupling means 100 joining one end of a pipe connection 102 to the interior of the cup member 72, and a second coupling device 104 by which connection is made between the pipe 102 and a part 106 of the fuel induction pipe 108. The part 106 constitutes an enlargement of one of the journal bosses on the exterior of the fuel induction pipe 108 for a shaft 110 of a butterfly throttle valve 112. A cooperating journal boss 114 is located substantially diametrically opposite to the boss 106, and both bosses are journaled at 116 and 118 respectively, to provide bearing surfaces for the throttle shaft 110.

A bore 120 is provided by the boss 106, which bore extends in a direction transverse to the axis of the throttle shaft, and opens at an orifice 121 into the journal bore 116 for the throttle shaft. The outer extremity of the bore 120 is enlarged and threaded as at 122 for the reception of the coupling device 104. A second bore 124 which may be referred to as a primary passage, is provided by the boss 106, and extends from the bore 120 through the wall of the fuel introduction pipe 108, to open with an orifice 126. In forming this second bore 124, it has been found convenient to drill through the boss 106 from the exterior surface thereof and across the bore 120, substantially as indicated in Fig. 4. A sealing plug 128 is then driven in the start end of the bore to seal the passage against the entrance of outside air.

The location of the bores 120 and 124, and the orifice 126 are so disposed and proportioned, one with respect to the other, that the effect of the fuel induction pressures within the member 108 can be critically controlled by rotation of the butterfly valve 112. It will be observed by reference to Figs. 1 and 2 that the primary passage 124 is so located as to be near the edge of the throttle valve 112 and wholly upon one side thereof when the throttle valve is closed, but will be transferred to the opposite side of the throttle valve when the throttle valve has been slightly opened. A throttle valve of the type illustrated, divides the fuel induction pipe into what may be characterized as a high pressure zone 130 on the carburetor side of the throttle valve, and a low pressure zone 132 on the engine side of the throttle valve. This condition will obtain so long as the throttle valve offers any material resistance to fluid movement through the pipe 108 from the carburetor side to the engine side of the valve. In each of the illustrated embodiments, in which a down-draft carburetor is illustrated, the high pressure zone will be repre-

sented by that portion of the fuel induction pipe above the throttle valve 112, while the low pressure zone will be that portion beneath the said throttle valve. Consequently, referring to Fig. 1, when the throttle valve 112 is closed during engine idling conditions, the primary passage 124 will open into and be exposed to the high pressure zone, on the carburetor side of the throttle valve, and when the throttle valve has been opened sufficiently as illustrated in Fig. 2 to transfer the port 126 to the opposite side of the throttle valve the primary passage 124 will thence open into the low pressure zone, on the engine side of the throttle valve. During the interim of changing the throttle position from Fig. 1 to Fig. 2, there will be a gradually effected change of pressure operating at the orifice 126. The changes are rapid, and the transition period is of such short duration that the resultant movement of the diaphragm within the contraction chamber is comparatively abrupt.

The resultant spark timing control, effected by a mechanism having in substance a single port in the fuel induction pipe located near the edge of the throttle valve and so situated as to be transferred to the opposite sides thereof upon opening the throttle valve, is sufficiently satisfactory to be incorporated for control of spark timing, over the lower speeds of the engine speed range. The spark timing curve effected by a mechanism of that character is indicated by the full line advance curve E of Fig. 12, and comprises the rapidly ascending branch c, joined by the substantially straight portion d, and the recurved portion e.

In Fig. 11, there are represented conditions curves, in which curve A is a vacuum curve for an automatic spark timing mechanism incorporating a single port or connection to the fuel induction pipe, of the character thus far described. It will be observed that this curve A has a comparatively rapid ascent from about $2\frac{1}{2}$ inches mercury depression at an engine speed of about 8 M. P. H. to about 18 inches mercury depression at an engine speed of about 25 M. P. H. The resultant of this rapid rise of vacuum potential is manifest in the comparatively abrupt shift, and slightly too early shift, of spark timing for the lower engine speeds. The corresponding spark timing shift effected by a mechanism so characterized, is represented by the branch c of the advance curve E shown in Fig. 12.

It will also be observed that the vacuum curve A in Fig. 11 flattens out somewhat and assumes a long gradual slope for engine speeds extending from the crest of the curve at about 32 M. P. H., through extreme high speeds. In general, the moment of force represented by the diminishing branch of the vacuum curve A is too powerful, and is too long continuing to produce the desired spark timing control for the higher engine speeds, particularly for those engine speeds greater than about 50 or 60 M. P. H. The spark timing advance resulting from the downwardly sloping portion of vacuum curve A, is particularly illustrated by the recurved portion e of the advance curve E shown in Fig. 12. The undesirable portion of the advance extends from about 52 M. P. H. through the higher speeds.

The instant invention contemplates improving the control of ignition timing at both the low and high speed end of the range of engine speeds, by producing a more gradual shift of automatic timing over the centrifugal timing at the end of engine idling speeds, and by diminishing and

finally cutting off the automatic spark advance above the centrifugal advance for the more extreme engine speed. The result attained is graphically illustrated by the conditions curve B of Fig. 11, and the results curve F of Fig. 12. The dashed line curve B represents the vacuum to which the fluid connection of the contraction chamber is exposed when applicant's invention is incorporated, the curve B comprising an upward sloping portion g of less steep beginning, and more uniform rate of increase than the vacuum curve A, and with a downward sloping portion h of considerably steeper slope, and in all extending over much less range of engine speeds, than the full line vacuum curve A. The interpretation of this dashed line curve B means that the vacuum potential within the fuel induction pipe will be of less abrupt effect for the lower speeds of the engine range, and will be of shorter duration, and of less moment during the higher engine speed, such that a substantial retraction of the contraction chamber may be secured for much lower engine speeds.

The resultant spark timing is represented by the curve F appearing in Fig. 12 where the dashed line portions represent the corrected spark timing relation at each end of the curve E, produced by applicant's improved mechanism. The intervening flat portion of the graph E is common with respect to both the full line advance curve, and the dashed line advance curve F. The dashed line portion F at the lower end of the revised spark timing curve, illustrates the more gradual shift of advance in timing, while the dashed line portion F of the curve extending between 52 and 60 M. P. H. illustrates the cut-off of spark timing for the higher engine speeds, due to the improved mechanism. By comparison of the two curves, it will be observed that the corrected advance of timing at about 12 M. P. H. is by the curve F about 20° ahead of top dead center, as compared with an advance of about 23° or more at the same speed by the curve E.

There appears on both Figs. 11 and 12 a curve designated C that represents the position of throttle opening for the various engine speeds. Two scales are associated with this curve C, one of which is graduated in degrees of throttle opening, appearing at the left hand margin of the figure, while the second scale is in percent of throttle opening, appearing at the right hand margin of the figure. For the purpose of comparison, the road torque throttle curve C is reproduced in both Figs. 11 and 12.

The improved novel construction for accomplishing the advance cut-off at the high speed end of the engine speed range, is illustrated in detail in Figs. 4 and 5. An interruptible passage is provided that operates to connect the primary passage 124 to the high pressure zone 130 of the fuel induction pipe, at a point in the throttle opening where it is desired to effect the advance cut-off. This interruptible passage comprises a cross bore or fluid passage 134 drilled through the rotatable throttle shaft 110, and so positioned as to provide fluid communication between the end of the bore 120 and the interior of the fuel induction pipe 108. In the illustrated embodiment the cross bore 134 extends diagonally across the shaft 110, so as to provide an orifice 136 opening into the interior of the fuel induction pipe 108 and situated on the carburetor side of the throttle valve. The other end of the passage 134 ends with an orifice 138 at the surface of the shaft 110 within the bearing bore 116, of the boss 106,

at such a point along the extent of the bore that the port 138 may be aligned with the open end or orifice 121 of the passage 120 at a certain angular position of throttle opening.

Referring to Figs. 1, 2 and 3, the relation of the ports and passages, contributing to the complete control of spark timing advance, will be observed to be such that in the idling position of the throttle 112, the contraction chamber 72 will be completely expanded, substantially as shown in Fig. 1, to give the initial spark timing setting represented by the branch *a* of curve D in Fig. 12. This is because the fluid connection of the chamber 84 is exposed to the high pressure zone 130 of the fuel induction pipe, due to the primary passage 124 being situated on the carburetor side of the throttle valve. Under these conditions of engine operation, that is when the throttle valve 112 is closed for idling, the high pressure zone 130 is substantially the same as atmospheric pressure. There is then, no fluid displacement within the chamber 84, by which a mechanical shift between the parts 14 and 20 could be effected, and consequently, the relation of the circuit breaking mechanism and operating cam is unaltered.

The contraction chamber 72 has been calibrated to operate upon about 5 inches of mercury displacement, and it will be observed by reference to Fig. 11, and the dashed curve designated B, that this mercury displacement of 5 inches occurs at about 10 M. P. H. On reference to Fig. 12, it will be noted that at the speed of about 10 M. P. H., there begins to be an advance in timing according to the advance curve F, and that the advance in timing effected is continuously increasing throughout an increased engine speed up to about 14 M. P. H., the total amount of advance being about 17° over and above the advance produced by the centrifugal mechanism represented by curve D, there being a total advance for an engine speed of about 14 M. P. H. to something like 27°. By reference to the curve C of Figs. 11 and 12, it will appear that the beginning of the suction created advance occurs when the throttle valve is opened about 5°, or at something like 6% of the total possible throttle opening, and that the suction created advance over the advance by centrifugal mechanism is completed at a throttle opening of about 7°, which is equivalent to 8 1/4 to 9% of the total amount of throttle opening.

Thus, it will be seen that the advance in ignition timing over the centrifugal mechanism for the low engine speeds, is the result of slightly increased opening of the throttle valve from the substantially closed or idling position illustrated in Fig. 1 toward that position illustrated in Fig. 2. However, the complete shift is effected at a point a little more than half way between the illustrated throttle openings of Fig. 1 and Fig. 2. The throttle opening illustrated in Fig. 2, amounts to an opening of about 12° above the position illustrated in Fig. 1, which amounts to about 15% throttle opening, and which occurs at about 25 M. P. H. engine speed, as will be seen by reference to the curves C appearing in Figs. 11 and 12.

The total amount of suction created spark timing shift over the advance by centrifugal mechanism, would be much greater than that illustrated by the curve E of Fig. 12, were it not for the fact that the stops provided by the parts 94 and 96 of the linkage between the contraction chamber 72 and clamp plate 20 limit the amount of suction actuated shift. The cooperation of

these elements of structure, make it possible to introduce an advance in spark timing by a suction control at about 10 M. P. H. engine speed, which control will gradually advance the timing to about 17° above the advance by the centrifugal mechanism, occurring at about 14 M. P. H., at which point the stops 94 and 96 will have been engaged, and from thence on maintain a fixed amount of timer shift over and above the advance in timing by the centrifugal mechanism during further increased engine speeds.

Upon reference to Fig. 12, it will be noted that at speeds from 50 to 55 M. P. H., it is desired to limit any further advance in timing, and that for speeds between 55 and 60 M. P. H., it is desired to reduce or cut off all of the suction controlled advance, such that spark timing control for increased engine speeds may be wholly effected by the centrifugal mechanism, and in accordance with the characteristics of the upper portion of the advance curve B. On reference to curve C, it will be noted that at 52 M. P. H., at which point it is desired to prevent any further advance in automatic timing, that the throttle valve is opened about 30°, which is equivalent to about 37 1/2% throttle opening. For this same throttle opening and road speed, it appears from Fig. 11 and the dashed line curve B, that the fluid pressure potential within the fuel intake pipe then amounts to about 12 inches of mercury depression, the moment of which is entirely too great to permit the membrane 82 of the contraction chamber to retract under the influence of the spring 86, since the contraction chamber 72 remains in the collapsed state for all pressure potentials greater than about 5 inches mercury depression.

The relation of the contributing elements effecting this high speed control is illustrated particularly in Fig. 3, where the throttle valve 112 has a 30° opening, which is equivalent to about 37 1/2%. Rotation of the throttle valve from the position illustrated in Fig. 1, to that position shown in Fig. 3, is accomplished by rotation of the shaft 110, and necessarily brings the orifice 138 of the cross bore 134 into communication with the orifice 121 at the bearing surface end of the bore or passage 120. Orifice 136 of the passage 134 always opens into the high pressure zone 130 of the induction fuel pipe, and it will thence be observed by reference to Figs. 3 and 4, that at the 30° throttle opening position, communication is established between the high pressure zone 130 and the passage 120 by means of the cross bore 134. Since the passage 120 and its fluid connection to the chamber 72 is exposed to the low pressure zone 132 through the primary passage 124, then the potential of the pressures within the induction pipe, both above and below the throttle valve, combine within the passage 120, the influence of which is transmitted to the contraction chamber 72.

As the throttle shaft approaches the position illustrated in Fig. 3 and continues in the opening movement, a greater modification of the pressure within the passage 120 is effected. As the throttle valve is opened there will be some valving effects in the interruptible passage due to the widening of the edges of the parts providing the orifices for the passages 134 and 120. In Fig. 3 this valving effect is illustrated to the effect that the orifice 138 is only partly opened to the orifice 121, in consequence of which a restriction is provided that permits only a partial modification of the pressure in passage 120. The potential of the

high pressure zone of the passage 134 is but partially effective upon the potential of the low pressure zone through the passage 124. As the throttle valve 112 is opened wider to a point where 5 this restriction is done away with, then the potential of the high pressure zone becomes fully effective and cancels the effect of the potential of the low pressure zone, to which the passage 120 is exposed through passage 124. This condition 10 occurs when the throttle valve is about half opened or at an angular setting of about 40° beyond the closed position of Fig. 1. On reference to Fig. 12 it will be observed that this condition occurs at speeds of about 60 M. P. H., or a little 15 more, at which point all spark timing advance by means of the contraction chamber is done away with, as represented by the upper branch of the curve F where it joins the curve E at j .

In Figs. 6 to 10 inclusive, there is illustrated a 20 modification of the construction for effecting the control at the high speed end of the range of engine speed. All parts of this construction in common or similar to the modification thus far described, are designated by the same reference 25 characters, while the elements of construction differing from those of the modification bear reference characters of the order of 200. The fuel induction pipe 108 is provided with a boss 206 through which there is the bore 116 providing one journal for the throttle shaft 110. A bore 220 is here provided that extends across and somewhat beyond the journal bore 116, and constitutes an elongation of the bore 120 of the first 30 modification, the starting end of the bore 220 being likewise threaded at 122 for reception of the coupling unit 104. In addition to the primary passage 124 opening into a high pressure zone above the throttle valve 112 when closed, there is a second bore 225 leading from the far 35 end of the bore 220 and ending with an orifice 227, situated so as to open into the high pressure zone 130 of the fuel induction pipe. The starting end of the bore 225 is closed by a plug 229 as in the instance of the primary passage 124. 40 Here the throttle shaft 110 is provided with a cross bore 234, so positioned and angularly disposed as to be alignable with the passage 220 upon sufficient rotation of the shaft 110. The cross bore 234 ends in orifices 236 and 238 performing similar functions to those of the cross bore 134 in the first modification, in that the orifice 236 is opened to the extended portion of the passage 220, and thence through the passage 225 and port 227, always in communication with the high pressure zone of the fuel induction pipe. 45

Fig. 7, illustrates the parts in throttle closed position where it will be observed that both passages 124 and 225 open to the high pressure zone on the carburetor side of the throttle valve 112. 50 However, due to the fact that the orifice 238 of the cross bore 234 is closed off by the bearing surface 116, there is no communication between opposite ends of the passage 220, and hence any contraction chamber that might be connected to the passage 220 at the threaded portion 122, is subjected to the high pressure zone of the fuel induction pipe only through the passage 124. The potential of the high pressure zone being insufficient to actuate the membrane 82 of the contraction unit, there will then be no shift in ignition timing. 55

In Fig. 8, the throttle valve has been adjusted to about a 12° opening, and in which instance the primary passage 124 is in effect transferred to the low pressure zone of the fuel induction pipe, or is 60

disposed on the engine side of the throttle valve. The low pressure zone has become sufficiently effective upon the contraction chamber long ere this throttle position is reached, to effect the initial advance in timing over the basic timing curve, 5 as has been explained hereinbefore. On reference to Fig. 12 it will be recalled that this shift takes place between 10 and 14 M. P. H. It will also be observed that the cross bore 234 still fails to provide any communication between the opposite ends of the passage 220. However, when the throttle valve 112 reaches a throttle opening of about 30°, which is illustrated in Fig. 9, there is sufficient communication established between the opposite ends of the passage 220 to permit of some 10 modification of the pressure potential upon the contraction chamber. Though the primary passage 124 opens into the low pressure zone of the fuel induction pipe, and in itself is sufficient to effectively operate the membrane 82 of the contraction chamber, the effective potential of the low pressure zone is modified by the potential of the high pressure zone through the passage 225 which always opens into the high pressure zone of the fuel induction pipe. That high pressure 20 potential is beginning to become effective through the cross bore 234, by reason of which there is a modification or reduction of the pressure moment in the fluid connection to the contraction chamber. This is illustrated by the curves D, F and C 25 appearing in Fig. 12, as has heretofore been explained.

In Fig. 10 there appears a layout of the principal elements of construction showing the relation of parts when the throttle valve is wide 30 open. When the throttle valve is wide open, there is such insufficient restriction of communication between the passages 124 and 225, and through the cross bore 234, that there is insufficient force to draw in the diaphragm or membrane 82. In consequence of this, the spring 86 retracts the membrane to the rest position, which results in cancellation of any advance by suction mechanism. This retracted position of the membrane of the contraction chamber takes 40 place as soon as the throttle valve has been opened sufficiently for the potential of the high pressure zone to cancel the potential of the low pressure zone. Upon reference of Fig. 12, it will be observed that this cancellation takes place 50 when the throttle valve is about half way opened. Note, for instance, that the lower end of the advance curve F intersects the centrifugal advance curve D at the point i , which is at about 60 M. P. H. The curve C indicates that the 55 throttle valve is opened about 40° or 50% of the total opening.

While the embodiment of the present invention as herein disclosed, constitutes a preferred form, it is to be understood that other forms 60 might be adopted, all coming within the scope of the claims which follow.

What is claimed is as follows:

1. The combination with an internal combustion engine having a throttle, and an ignition 65 timer for said engine, of means controlled by the suction of said engine for adjusting the timer, and means including a throttle actuated valve rendering the suction controlled means non-responsive to suction potential while the throttle 70 is positioned at the high speed end of the engine speed range.

2. The combination with an internal combustion engine having a throttle, and an ignition timer for said engine, of means controlled by 75

the suction of said engine for adjusting the timer, and means including an interruptible passage for diminishing the effect of the suction control when the throttle is positioned for the higher speeds 5 of the engine speed range.

3. The combination with an internal combustion engine having a throttle, and an ignition timer for said engine, of means controlled by the suction of said engine for adjusting the timer, 10 and means including a normally closed passage for cutting off the suction effect during throttle opening for high speed engine operation.

4. The combination with an internal combustion engine having a fuel induction pipe, a throttle valve dividing the pipe into a high pressure zone and a low pressure zone, ignition timer mechanism, and means influenced by the vacuum created in the fuel induction pipe, when the engine is operating at throttle opening giving 20 speeds above idle speed for altering the timer mechanism, of connecting means between the altering means and the induction pipe for operating the timer altering means in response to the potential of the low pressure zone, and means 25 including an interruptible passage leading to the high pressure zone of the induction pipe for cutting off the potential of the low pressure zone to the connecting means during engine operation under throttle opening over the upper third portion 30 of the engine speed range above idling.

5. In an internal combustion motor, having an intake passage in which suction is created by operation of the engine, the combination comprising, an ignition timer, movable means for 35 shifting the timer for timing the ignition, said movable means being actuated by the suction potential created in the intake passage, with a by-pass to a higher pressure within the intake pipe for variably controlling the effective suction 40 on the timer shifting, means whereby the suction will be insufficient to operate the movable means during the extremes of throttle opening, said means operating to cause an effective tension on the movable means to effect a sudden 45 advance in spark timing at a throttle position just above the idle speed band, and to effect a sudden retard in spark timing just prior to throttle opening for the high speed extreme of the engine speed range.

50 6. In an internal combustion motor, having an intake passage in which suction is created by operation of the engine, the combination comprising, an ignition timer, movable means for 55 shifting the timer for timing the ignition, said movable means being actuated by the suction potential created in the intake passage, with a by-pass to a higher pressure within the intake pipe for variably controlling the effective suction on the timer shifting means whereby the same will 60 be insufficient to operate the movable means during the extremes of throttle position, said means operating to cause an effective tension on the movable means to effect a sudden advance in spark timing at about 6% engine throttle opening, and to effect a sudden retard in spark timing at about 40% engine throttle opening.

7. In an internal combustion motor, an intake passage in which suction is created by the running of the motor, an igniter including a movable timer element for timing the ignition, a 70 movable device including a suction responsive chamber, with means for actuating the timer element, a connection between the chamber and the intake passage, an interruptible passage opening into the connection, a throttle valve in the

intake passage dividing the passage into high and low pressure zones, said suction responsive chamber being exposed to the high pressure zone of the intake pipe while the throttle is opened during engine idling operation and thereby effecting no timer alteration, movement of the throttle valve exposing the chamber to the low pressure zone of the intake passage at throttle positions greater than about 10% of the total throttle opening, thereby effecting a timer alteration for all throttle positions above that for idling speed, and means including the interruptible passage exposed to the high pressure zone for cancelling the timer alteration by the suction chamber while the throttle is opened during 15 the higher third portion of the engine speed range above idling.

8. In an internal combustion motor, having an intake passage in which suction is created by the running of the motor, and in which a throttle valve divides the passage into a high pressure zone and a low pressure zone, the combination including an igniter provided with a movable timer element for timing the ignition, means providing a normal timer control in accordance with 25 a basic timing curve, a chamber operable upon the timer element with means for putting said chamber into communication with the low pressure zone of the intake passage for at least 35% of the engine throttle opening, for altering the 30 timing of ignition from the basic timing curve, and means for putting said chamber into communication with the high pressure zone of the induction pipe for at least 30% of the engine 35 throttle opening and when the throttle is opened two-thirds or more of its range, for restoring the altered timing of ignition to the basic curve, during engine operation under practically wide open throttle.

9. In an ignition controller, the combination 40 with an engine having a fuel induction pipe, and a throttle valve in the fuel pipe providing high and low pressure zones on opposite sides thereof, of an ignition timer, a suction device for setting the same, means connecting the device 45 with the fuel induction pipe and comprising, a passage with a port opening into the high pressure zone of the fuel pipe when the throttle valve is closed, but shiftable to the low pressure zone as the throttle valve is opened for engine speeds 50 above idling, and a branch passage with an interruptible portion provided by the throttle valve, adapted to open into the high pressure zone at predetermined throttle positions, whereby the device will fail to respond to the potential of the 55 high pressure zone for throttle positions less than about 6% and more than about 50% of possible throttle opening, but will respond to engine produced suction between 6% and 50% of possible 60 throttle opening to effect setting of the ignition timer.

10. In an ignition controller, the combination with an engine having a fuel induction pipe, and a throttle valve in the fuel pipe providing high and low pressure zones on opposite sides thereof, 65 of an ignition timer, a suction device for setting the same, means connecting the device with the fuel induction pipe and comprising, a passage with a port opening into the high pressure zone of the fuel pipe when the throttle valve is closed, but shiftable to the low pressure zone as the 70 throttle valve is opened for engine speeds above idling, and a branch passage with an interruptible portion provided by the throttle valve, adapted to open into the high pressure zone at 75

predetermined throttle positions, whereby the device will fail to respond to the potentials of the fuel pipe for throttle positions up to about 6% opening and for throttle positions above about 50% of possible throttle opening, but will respond to engine produced suction for throttle positions between 6% and 50% of possible throttle opening to effect setting of the ignition timer.

11. In an ignition controller, the combination with an engine having a fuel pipe, and a throttle valve on a shaft journalled in bosses provided by the fuel pipe, and separating the pipe into high and low pressure zones, of an ignition timer, a suction device for setting the same, means connecting the device and the fuel pipe, and including passages located in one of the fuel pipe bosses and the throttle shaft for selectively exposing the device to the potentials of both pressure zones in the fuel pipe, the passage in the throttle shaft having interruptible communication with the passage in the boss and always opening into the high pressure zone of the fuel pipe, for cancelling the effect of the low pressure zone upon the device at a predetermined throttle opening.

12. In an ignition controller for internal combustion engines, the combination of, a timer device, and means controlled by the suction of the engine, having provisions for obtaining a relatively quick advance of spark at about 5% engine throttle opening, and a relatively quick retard of spark at about 40% to 50% engine throttle opening, and means establishing a basic spark timing curve, from which the provisions effect the advance, characterizing a uniform angular relation for engine speeds up to about 7% engine throttle opening, and thence a substantially uniformly advancing speed controlled relation up to about 65% engine throttle opening, said provisions effecting a predetermined timer advance above the basic timing substantially throughout the throttle opening range between about 5% and 50% engine throttle opening.

13. In an internal combustion motor, having an intake passage in which suction is created by operation of the engine, and in which a throttle valve tends to separate the passage into high and low pressure zones during engine operation, and having an ignition timer with suction responsive means for controlling the ignition timing, the combination of means regulating the application of suction from both zones to the suction responsive means, said regulating means including an uninterrupted primary passage opening into the high pressure zone of the intake passage and near the edge of the throttle valve at less than 6% throttle opening, an interruptible by-pass for the primary passage that remains closed up to about 40% throttle opening, whereby a rapid automatic advance in ignition timing is effected at about 6% throttle opening, and a diminution of timing advance is effected for 40% or greater throttle opening.

14. In an internal combustion engine having a fuel pipe provided with a throttle valve, separating the pipe into high and low pressure sides, said fuel pipe being subject to variations in engine produced suction incident to self-operation, ignition apparatus comprising in combination, a circuit breaker, a cam for operating the breaker, and means responsive to engine produced suction for varying the angular relation between the cam and breaker, said means including a suction chamber having communication by a primary

passage with a port in the fuel pipe located on the high pressure side of the throttle valve and near the edge of the valve when closed, but exposed to the low pressure side of the throttle valve when the valve has a 6% or greater opening, and means providing a secondary passage joining the primary passage and having interruptible communication with the high pressure side of the throttle valve for modification of the pressure in the primary passage at 40% and 10 greater throttle openings.

15. The combination set forth in claim 14, in which the means providing the interruptible communication include a cross bore in the throttle shaft continually exposed to the high pressure side of the fuel pipe and one end of which normally ends at the bearing surface of the throttle shaft, and which is alignable with a branch of the primary passage at a predetermined point of throttle opening.

16. In an automatic timing control for ignition distributors, the combination comprising, a timer having a movable part for altering the time of ignition, an expansion chamber adapted to actuate the movable part, a fuel induction pipe provided with a rotatable shaft supported throttle valve for admitting fuel to the engine cylinders, and means connecting the chamber with the induction pipe, said means including a boss on the induction pipe surrounding the throttle shaft and providing a passage ending at the surface of the shaft, and a lateral branch of the passage opening into the induction pipe adjacent the edge of the throttle so as to be exposed to the carburetor side thereof when the throttle valve is closed, but exposed to the engine side of the throttle valve when opened greater than for idling, and means including a passage provided by the throttle shaft, and registrable with the first mentioned passage end, for exposing the connecting means to the carburetor side of the induction pipe during 40% or greater throttle opening.

17. In an automatic timing control for ignition distributors, the combination comprising, a timer having a movable part for altering the time of ignition, an expansion chamber adapted to actuate the movable part, a fuel induction pipe provided with a rotatable, shaft supported throttle valve for delivering fuel to the engine cylinders, and means connecting the chamber with the induction pipe, said means including a boss on the induction pipe surrounding the throttle shaft and providing a passage ending at the surface of the shaft, and means including a passage provided by the throttle shaft for by-passing the exposed connection of the first mentioned passage to the engine side of the throttle valve as the shaft is rotated toward open position, one end of the throttle shaft passage always being open to the carburetor side of the induction pipe, while the other end thereof is closed off by the shaft bearing surface during throttle closed positions less than about 40% and greater throttle opening.

18. In automatic control mechanism for ignition timers, wherein an expansion chamber is in communication with the fuel induction pipe and responds to the suction potential within the fuel induction pipe for shifting the time of ignition, and wherein a shaft supported throttle valve is rotatable across the fuel pipe for regulating the amount of fuel admitted to the pipe, the combination with said chamber of means connecting the chamber to the fuel induction pipe for regulating the effect of the suction potential.

- upon the chamber, whereby the chamber will be non-responsive to the suction potential below 6% and above 53% throttle opening for effecting a predetermined shift in ignition timing, said connecting means including a passage opening into the fuel pipe at the edge of the throttle valve and exposed to the engine side thereof when the throttle valve is opened more than about 6% of total throttle opening, a second passage opening 10 into the fuel pipe and always exposed to the carburetor side of the throttle valve, but normally out of communication with the first mentioned passage, and means including rotation of the throttle shaft for establishing communication 15 between the passages at a predetermined throttle opening, whereby the connecting means to the chamber is subjected to a resultant of the suction potentials on both sides of the throttle valve at and above about 40% throttle opening.
19. In mechanism for controlling ignition timing in response to the suction potential within an engine intake pipe, the combination with the intake pipe of a butterfly throttle valve, a rotatable shaft supporting the valve and having bearings 20 in the walls of the pipe, means providing a passage having a port opening into the fuel pipe at the edge of the valve so as to be exposed to low pressure potential when the valve is opened beyond about 6% of its possible opening, said 25 passage ending at one of the bearing surfaces for the rotatable shaft, and a passage provided by the shaft for exposing the first mentioned passage to a high pressure potential within the intake pipe when the throttle valve is more than 30 about $\frac{1}{3}$ open.
20. In mechanism for controlling ignition timing in response to the suction potential within an engine intake pipe, the combination with the intake pipe of a butterfly throttle valve, a shaft 35 journaled in bearing bosses provided by the pipe, for rotatably supporting the butterfly valve across the pipe, said throttle valve tending to separate the pipe into high and low pressure zones, a passage provided by one of the bearing bosses having a port opening into the pipe near the edge of the butterfly and exposed to the high pressure zone while the butterfly valve is substantially closed, but exposed to the low pressure zone of the intake pipe as the butterfly valve reaches a 40% opening, and means including a passage 40 through the shaft for exposing the first mentioned passage to the high pressure zone of the intake pipe as the butterfly valve reaches a 45% opening.
21. In a suction controlled timer for internal combustion engines wherein an expansion chamber has fluid connection with an induction fuel pipe, the combination with the fluid connection of means exposing the connection to relatively 50 high pressure within the fuel pipe while the throttle valve is nearly closed, and to relatively low pressure for increased throttle openings, and means exposing the connection to both high and low pressures within the fuel pipe at a predetermined throttle opening, whereby the suction control is rendered non-effective for substantially wide open throttle operation.
22. The combination with an internal combustion engine having a fuel pipe, a butterfly throttle valve therein, and an ignition timer for said engine, of means controlled by the engine suction produced within said fuel pipe for adjusting the timer, and means modifying the control by suction, said modifying means including a port 55 and passage opening into the fuel pipe and exposed to the carburetor side of the throttle valve when open less than about 6%, means effecting a substantially fixed amount of 60 advance in spark timing for engine operation with more than slight throttle opening, comprising means for exposing the said port and passage to the engine side of the throttle valve as the valve is opened more than about 6%, and means 65
- posed to the carburetor side of the throttle valve when open less than 6%, means for exposing the said port and passage to the engine side of the throttle valve as the valve is opened more than 6%, and means comprising an additional 5 passage for exposing the first numbered passage to the carburetor side of the throttle valve at about 40% throttle opening.
23. The method of controlling the suction admitted to the suction unit of a timing control 10 mechanism for internal combustion engines, having a fuel induction pipe with a throttle valve, a timer, and a suction unit for shifting a timer part, said method comprising the steps in combination, subjecting the unit to the relatively high 15 pressure only on the carburetor side of the throttle valve while the valve is but slightly open, subjecting the unit to the relatively low pressure only on the engine side of the throttle valve, while increasing the throttle opening from slightly open 20 to almost half open, and thence, also subjecting the unit to the relatively high pressure on the carburetor side of the throttle valve as the opening of the throttle valve is increased to the half open position.
24. The method of controlling automatic timing for internal combustion engine, comprising the steps in combinations, establishing fluid connection between a contraction chamber and a high pressure zone of the full induction pipe, 30 while the engine throttle is practically closed, shifting the fluid connection from the high pressure zone to a low pressure zone of the fuel induction pipe as the throttle is opened slightly beyond the practically closed position, and thence 35 opening the fluid connection to the high pressure zone without disturbing the connection to the low pressure zone as the engine throttle approaches the half open position.
25. The method of controlling the movement 40 of a suction operated device for shifting the timing of an internal combustion engine, comprising the steps of bringing the device into fluid communication with a relatively high pressure zone of the engine intake pipe while the throttle 45 valve is substantially closed, shifting the fluid communications from the said high pressure zone to a relatively low pressure zone of the intake pipe, as the throttle valve is slightly increased in opening, maintaining communication with the low 50 pressure zone for all throttle positions greater than the slight throttle opening, and also making a fluid communication with the high pressure zone of the engine intake pipe before the throttle 55 is increased to half open position without interrupting the communication with the low pressure zone.
26. The combination with an internal combustion engine having a fuel pipe, a butterfly throttle valve therein, and an ignition timer for said 60 engine, of means controlled by the engine suction produced within said fuel pipe for adjusting the timer, and means modifying the control by suction, said modifying means including means effecting a retard of spark timing during engine 65 operation with slightly opened throttle, comprising a port and passage opening into the fuel pipe and exposed to the carburetor side of the throttle valve when open less than about 6%, means effecting a substantially fixed amount of 70 advance in spark timing for engine operation with more than slight throttle opening, comprising means for exposing the said port and passage to the engine side of the throttle valve as the valve is opened more than about 6%, and means 75

effecting a reduction of advance in timing for engine operation under substantially half open throttle, comprising a passage exposed to the carburetor side of the throttle valve, and means 5 adapted to inter-connect both passages at about 40% throttle opening.

27. In a suction controlled timer for internal combustion engines wherein an expansion chamber has fluid connection with an induction fuel 10 pipe, the combination with the fluid connection of means exposing the connection to relatively

high pressure within the fuel pipe while the engine is operating under slightly open throttle, and to relatively low pressure for engine operation at throttle openings more than slightly open, and means exposing the connection to both 5 high and low pressures within the fuel pipe at a predetermined throttle opening, whereby the suction control is rendered non-effective during engine operation under substantially wide open throttle.
